UNITED STATES PATENT OFFICE.

RAYMOND R. RUNDELL, OF ELMIRA, NEW YORK, ASSIGNOR OF ONE-THIRD TO
GEORGE C. HAESLOOP, OF ELMIRA, NEW YORK.

COMBINED CHECK AND CLOSER.

1,425,900.

Specification of Letters Patent. Patented Aug. 15, 1922.

Application filed October 18, 1921. Serial No. 508,489.

To all whom it may concern:

Be it known that I, RAYMOND R. RUND
DELL, a citizen of the United States, residing
at Elmira, in the county of Chemung and
5 State of New York, have invented certain
new and useful Improvements in Combined
Checks and Closers, of which the following
is a specification.

The invention relates to automatic checks
10 and closers which are employed for the
purpose of preventing any body which is
so arranged and constructed to have a to-
and-fro motion with respect to a fixed sup-
port to automatically return to said fixed
15 support when displaced therefrom without
being violently slammed against said fixed
support, and is more particularly adapted
for use as a door check and closer.

The objects of the invention are:
20 First, to construct a check and closer of
the nature above indicated consisting of a
minimum number of parts which may be
easily and cheaply manufactured and as-
sembled, installed, adjusted or taken apart
25 with ease and without the use of skilled
labor.

Second, to provide a check and closer
which embodies mechanism adapted to auto-
matically adjust itself to wear and at the
30 same time provide a uniform tension or
friction of the cooperating parts controlling
the closing and checking functions of the
device.

Third, other objects and advantages of
35 the invention will appear from the detailed
description of the construction, mode of as-
sembling and operation of the same to be
presently disclosed.

The invention consists of structural char-
40 acteristics and relative arrangements of ele-
ments which will be hereinafter more fully
described and particularly pointed out in
the appended claims.

In the drawings, in which similar ref-
45 erence characters indicate the same parts in
the several figures,

Figure 1 is a longitudinal section of the
improved check and closer.

Figure 2 is a transverse section taken on
50 line II—II of Figure 1.

Figures 3, 4, 5 and 6 are plan views of
modified forms of the ratchet spring.

Figure 7 is a longitudinal section of a
modification of the invention.

Figure 8 is a section taken on line VIII— 55
VIII of Fig. 7.

Referring to Figures 1 and 2 of the draw-
ings, 10 is a bracket or support having
upper and lower annular extensions or ends
11 and 12 and is adapted to be secured to a 60
door D, or other movable element by means
of screws 13, 13, as shown. Interposed be-
tween and engaging the inner sides of the
annular extensions or ends 11 and 12 is a 65
hollow cylindrical casing 14 having its ends 65
knurled or roughened at 141 to engage
similar roughened or corrugated inner sides
of the extensions or ends 11 and 12 to pre-
vent said casing 14 from turning while seat-
ed in the bracket 10 and engaged by the 70
flanges 15 on said ends 11 and 12 of the
bracket.

Said casing 14 is provided at its ends with
internal screw threads 142 adapted to be
engaged by top cap 16 and bottom cap 17, 75
and when said caps 16 and 17 are firmly
screwed down or seated against the outer
sides of the annular extensions 11 and 12,
said casing 14 is firmly and immovably held
within the bracket 10, as will be readily 80
understood. Said top cap 16 is also pro-
vided with sockets 18, 18, while the bottom
cap 17 has diametrically opposed slots 19
to be engaged by a spanner wrench or other
proper tool for the purpose of tightening 85
up or adjusting this class of constructions.

20 is a rotatable shaft or post arranged at
the center or axis of the casing 14 and is so
arranged that its upper end passes loosely
through an opening 21 in the top cap 16, 90
while its lower end is rotatably seated in a
central socket 22 formed on the inside of the
bottom cap 17, said shaft or post 20 being
retained in said socket 22 by means of a
coil spring 23 interposed between a shoul- 95
der 231 formed on said shaft or post and a
circular recess 232 on the inside of top cap
16, as shown.

24 is a coil spring within and at the lower
end of the casing 14, one end of which 100
spring is passed through or rigidly secured
to the lower end of the shaft or post 20
while the other end of said spring 24 is
anchored to a pin 25 attached to and pro-
jecting through the bottom cap 17.

Within the casing 14 and frictionally in
contact with the inner surface thereof is a
retarder sleeve 27 which may be and is pref-

erably split to form a slit at 28, as shown, and provided on its inner surface with a series of separated grooves or recesses 29, 29, for purposes to be presently explained.

5 30 is a ratchet spring which consists preferably of a coiled broad strip or band of thin sheet metal and arranged within the retarder sleeve 27 having one edge or straight section 31 passing through a slot

10 32 in the rotatable shaft or post 20, while its outer or free edge 33 is turned outwardly and adapted to pass into any one of the series of grooves or recesses 29, 29, formed in the retarder sleeve 27 in a manner to be 15 hereinafter disclosed.

34 is an adjustable locking ring at the bottom of the casing 14 and is provided with a knurled outer edge, and internal threads adapted to engage the threads on 20 the outer cylindrical surface of the bottom cap 17 and capable of locking the position or extent into which said cap 17 is secured into the casing 14.

The construction of the modification 25 shown in Figs. 7 and 8 is substantially the same as illustrated in Figs. 1 and 2, except that the casing 140 is made integral with the supporting bracket or lug 101 by brazing or otherwise, and the rotatable post or shaft 30 201, spring 241, retarder sleeve 271 with its grooves 291 and ratchet spring 301, caps 161 and 171 are substantially in the same relation as shown in Figs. 1 and 2, except a disk or plate 242 is interposed between the spring 35 241 and the adjacent or lower end of the ratchet spring 301. The spring 241 is anchored to a bolt 251 passing through a threaded opening in bottom cap 171. This form of the invention is intended for use in 40 connection with elements of lighter weight than that shown in Figs. 1 and 2.

The construction of the ratchet springs 30 and 301 shown in Figs. 1 and 2, and 7 and 8, may be varied in many ways and if desired may assume the form shown in Figure 3 when it is desired that said spring have two engaging ends 40 and 40. Figure 4 shows a form of spring which would tend to store up potential energy and thereby easily 50 overcome any possible tendency of the retarder sleeve 27 from sticking. Figure 5 illustrates a type which would be adapted to engage a key-way in the shaft and post by means of the bent-in end 41, while Figure 6 55 illustrates a construction capable of being secured to a shaft or post square in cross section by means of the inner rectangular end 42.

The parts being arranged as shown in Figures 1 and 2 and the upper or outer end of the shaft 20 having been pivotally connected to a fixed point by means of a link L, shown in dotted lines, and oil having been placed within the casing 14 to act as a lubricant, 60 65 the operation of the invention is as follows:

As the movable or hinged element or door D is swung around on its pivot it carries with it the bracket 10 and connected casing 14, during which movement the shaft or post 20 is made to rotate in the direction, as indicated by the arrow, in Figure 1. This rotation of the shaft or post 20 is resisted by and stores up energy in the spring 24 and at same time causes the ratchet spring 30 to rotate in the direction shown by the arrow 70 in Fig. 2, which movement has a tendency to wind up and decrease the diameter of said spring 30 and hence reduce the frictional effect of the spring against the inner wall of the retarder sleeve 27 and thereby permit 75 the bent end or edge 32 of said spring to easily slide over said inner wall without disturbing or tending to move or rotate the retarder sleeve 27. After the door D, or other moving element has reached the end of this 80 motion, by the action of the stored energy in spring 24, the shaft or post 20 has a tendency to rotate in a direction opposite from that indicated by the arrows in Figures 1 and 2, and hence said door D is forced to 85 return to its initial position. As the shaft 20 rotates in the opposite direction, it carries with it the ratchet spring 30 which permits said ratchet spring to expand to its former diameter and at the same time allows 90 its edge or end 32 to engage or spring into one of the grooves 29, 29, in the retarder sleeve 27, and during the further movement of the ratchet spring 30, said retarder sleeve 95 being in frictional engagement with the casing 14, is dragged with said ratchet spring 30 and acts as a resistance to the movement or rotation of the shaft 20 by the spring 24 and therefore checks up or retards the movement of the door D or other element. 100

It will also be seen that owing to the retarder sleeve 27 being split at 28 and assembled under initial tension, the frictional resistance between the casing 14 and said sleeve 27 is automatically kept constant, although said parts may wear from repeated and continuous operation of the combined closer and check for the reason the expansion of the ratchet spring 30 has a tendency also 110 to further expand the retarder sleeve 27. 115

Should it be found that the turning effect or adjustment of the spring 24 is not proper for the conditions under which the device is to be operated, the torsional strength of said spring 24 may be modified by turning the bottom cap 17 either to the right or left and locking it in its adjusted position after proper regulation by means of the locking ring 34, as will be readily understood and needs no further disclosure. 120

It will be seen from the herein-described constructions, mode of assembling and cooperation of the parts, that all the objects and advantages recited in the statement of invention have been fully and efficiently car- 125 130

ried out, and although two forms are disclosed, many changes and other modifications will readily suggest themselves without departing from the essential features 5 and scope of the present invention, as for example, the retarder sleeve 27 or the slit 28 and grooves 29 in the retarder sleeve 27, and turned up edge or end 30 of the ratchet spring 29 may be dispensed with as they are 10 not absolutely necessary for the operation of the device.

What I claim is:

1. A combined closer and check device comprising a fixed cylindrical casing, a rotatable shaft disposed at the axis of the cylindrical casing, a retractile ratchet spring within the cylindrical casing having an end connected to the rotatable shaft and its disconnected section adapted to engage and 15 disengage the inner surface of said casing, and a spring having one end connected to said fixed casing and its other end secured to the rotatable shaft.

2. A combined closer and check device comprising a fixed cylindrical casing, a retarder sleeve fitted within and adapted to frictionally engage the inner surface of said casing, a rotatable shaft disposed within the cylindrical casing, a ratchet spring within 20 the retarder sleeve having one end connected to the rotatable shaft and its other end adapted to engage and disengage the inner surface of said retarder sleeve, and a spring having one end fixed and its other 25 end secured to the rotatable shaft.

3. A combined closer and check device comprising a fixed cylindrical casing, a retarder sleeve fitted within and adapted to frictionally engage the inner surface of said 30 casing, a rotatable shaft disposed within the cylindrical casing, a band coil spring within the retarder sleeve having one end connected to the rotatable shaft and its outer curved surface adapted to frictionally engage and disengage the inner surface of 35 said retarder sleeve, and a spring having one end fixed and its other end secured to the rotatable shaft.

4. A combined closer and check device comprising a fixed cylindrical casing, a retarder sleeve having a series of separated recesses on its inner surface and fitted within and adapted to frictionally engage the inner surface of said casing, a rotatable 50 shaft disposed within and at the axis of the cylindrical casing, a ratchet spring within

the retarder sleeve having one end connected to the rotatable shaft and its other end turned outwardly and adapted to engage and disengage the recesses in the inner surface of said retarder sleeve, and a spring having one end connected to said fixed casing and its other end secured to the rotatable shaft.

5. A combined closer and check device 65 comprising a hollow fixed cylindrical casing, a split retarder sleeve fitted within and adapted to frictionally engage the inner surface of said casing, a rotatable shaft disposed within and at the axis of the cylindrical casing, a ratchet spring within the retarder sleeve having one end connected to the rotatable shaft and its other end adapted to engage and disengage the inner surface of said retarder sleeve, and a spring 70 having one end connected to said fixed casing and its other end secured to the rotatable shaft.

6. A combined closer and check device comprising a fixed cylindrical casing, a split 80 retarder sleeve having a series of separated grooves on its inner surface and fitted within and adapted to frictionally engage the inner surface of said casing, a rotatable shaft disposed within and at the axis of the cylindrical casing, a ratchet spring within the retarder sleeve having one end connected to the rotatable shaft and its other end turned outwardly and adapted to engage and disengage the grooves in the inner surface of said retarder sleeve, and a 85 spring having one end connected to said fixed casing and its other end secured to the rotatable shaft.

7. A combined closer and check device 90 comprising a fixed cylindrical casing, a retarder sleeve fitted within and adapted to frictionally engage the inner surface of said casing, a rotatable shaft disposed within and at the axis of the cylindrical casing, a 100 ratchet spring within the retarder sleeve having one end connected to the rotatable shaft and its other end adapted to engage and disengage the inner surface of said retarder sleeve, a torsional spring having one end connected to said fixed casing and its other end secured to the rotatable shaft, and means for adjusting said torsional spring.

In testimony whereof I affix my signature.

RAYMOND R. RUNDELL.
